United States Patent [19]

Benedict et al.

[11] Patent Number: Des. 428,418

[45] Date of Patent: ** Jul. 18, 2000

[54] ARM AND COMPUTER PAD SUPPORT

5,490,710 2/1996 Dearing et al. .
5,876,002 3/1999 White et al. .[75] Inventors: **Duncan J. Benedict; Shu-Ling Benedict**, both of Worcester, Mass.Primary Examiner—M. H. Tung
Attorney, Agent, or Firm—Robert J Doherty[73] Assignee: **Flair Industries, Inc.**, Providence, R.I.[57] **CLAIM**[**] Term: **14 Years**

The ornamental design for an arm and computer pad support, as shown and described.

[21] Appl. No.: **29/106,058**

DESCRIPTION

[22] Filed: **Jun. 9, 1999**FIG. 1 is a top, front perspective view of an arm and computer pad support, on a reduced scale;
FIG. 2 is a top perspective view thereof;
FIG. 3 is a left side elevational view of FIG. 2;
FIG. 4 is a right side elevational view of FIG. 2;
FIG. 5 is a top plan view of FIG. 2;
FIG. 6 is a bottom plan view of FIG. 2;
FIG. 7 is a front elevational view of FIG. 2;
FIG. 8 is a rear elevational view of FIG. 2;
FIG. 9 is a top perspective view thereof, the support is shown in an alternate position; and,
FIG. 10 is a left side elevational view of FIG. 9.[51] LOC (7) Cl. **14-02**

The broken line showing of a chair and connection element in FIG. 1 is for illustrative purposes and forms no part of the claimed design.
